UNITED STATES PATENT OFFICE.

WILLIAM H. A. WILLIAMS, OF BENNETTSVILLE, SOUTH CAROLINA.

APPARATUS FOR TUFTING MATTRESSES.

1,298,847.

Specification of Letters Patent.

Patented Apr. 1, 1919.

Application filed May 22, 1918. Serial No. 237,268.

To all whom it may concern:

Be it known that I, WILLIAM HENRY ARNOLD WILLIAMS, a citizen of the United States, residing at Bennettsville, in the county of Marlboro and State of South Carolina, have invented certain new and useful Improvements in Apparatus for Tufting Mattresses, of which the following is a specification, reference being had to the accompanying drawings.

This invention relates to mattress making machinery, and particularly to means for "tufting" mattresses.

The general object of my invention is the provision of means whereby a plurality of needles may be passed through the stuffed mattress simultaneously, the needles carrying the tufting cords.

A further object is the provision of means whereby the mattress may be clamped in front of the needles and whereby the needles may be supported while they are being forced into the mattress so that the needles will not bend.

A further object is to provide a machine of this character which is very simple in construction and operation, has few parts, and which may be readily operated for the purpose intended.

My invention is illustrated in the accompanying drawings, wherein:—

Figure 1 is a side elevation of the device;

Fig. 2 is a horizontal section on the line 2—2 of Fig. 1;

Fig. 3 is a transverse section on the line 3—3 of Fig. 2; and

Fig. 4 is a detail view of the needle supporting bar.

Referring to the drawings, it will be seen that one element of my machine is a main frame constructed of longitudinally extending members 10 and vertical members 11. These longitudinal and vertical members 10 and 11 are connected to each other by transverse braces 12 and constitute a rectangular or cubical frame, the rear end of which is braced by the crossed braces 13. The lower longitudinal members 10 extend in front of the forward braces 12 to provide a platform 14 upon which a mattress is designed to be supported, the mattress being disposed on

edge. Extending from the forward transverse braces 12 to the platform 14 are a plurality of vertically disposed, uniformly spaced rods 15, and hingedly mounted upon the forward edge of the platform 14 is a mattress clamping frame 16 having longitudinally extending rods 16^a, which are spaced from each other a uniform distance. The mattress clamping frame 16 may be held in a vertical position and against a mattress by means of the hooks 17 and the frame 16 is preferably provided with legs 18, which are pivoted to the mattress supporting frame so as to swing to a vertical position when the mattress supporting frame is horizontal. It will be obvious now that a mattress may be disposed upon the clamping frame 16 and then this frame swung upward and engaged by the hooks 17, whereupon the mattress will be clamped upon the rods of the frame 16 and the rods 15.

Mounted for longitudinal movement within the frame composed of the members 10, 11 and 12 is a needle supporting frame, designated generally 19. This is also composed of longitudinal members 20, vertical members 21 and transverse members 22. This frame 19 is supported upon lower pairs of wheels 23 which bear upon tracks 24 attached to the lower members 10 and also carries the upper pairs of wheels 25 which operate on tracks supported on the upper members 10. By this means, the frame 19 may be readily shifted longitudinally within the main frame. At the front of the frame 19 are disposed the vertical uniformly spaced slats 26, each carrying a plurality of forwardly pointing needles 27. These needles may be arranged in any desired manner, but as illustrated the needles are arranged in pairs, the pairs being disposed in transversely extending series.

Disposed within the frame 19 is a needle guide supporting frame 28 comprising the longitudinally extending slats or beams 29, the vertically extending slats or beams 30, and transverse connecting members 31. The upper and lower beams or slats 29 are extended beyond the forwardmost vertical members 30 and are designed to pass through spaces between the bars 26. The

forward ends of these members 29 are connected by transverse bars 32 and mounted upon these transverse bars are the vertical needle supporting rods 33, these rods being 5 notched as at 34 to receive the needles, there being a notch for each needle. The frame 28 is supported by wheels 35 which roll on tracks 36 mounted upon the lower members 20, and the upper end of the frame 28 also 10 carries the wheels 37 which bear upon tracks attached to the under faces of the upper members 20. It will be seen from this that the frame 19 can be pushed along within the main frame and that the frame 28 can be 15 shifted independently within the frame 19. The needles are formed to support suitable cords to be passed through the mattress.

In the use of this invention, the mattress is disposed as before explained, between the 20 mattress clamp and the bars 15. At this time the frame 28 has been shoved fully forward so that the notches 34 are at the extremities of the needles and the frame 19 is pushed forward by means of the handle 38. 25 The cross bars 32 will now engage with the bars 15 and will be held from further forward movement while the needles are forced into and through the mattress by the continued forward movement of the frame 19. 30 The notches 34 act to support the needles adjacent the face of the mattress so that the needles will not bend or become deflected in passing through. When the needles and the tufting cords have been passed through the 35 mattress the needles are withdrawn by drawing back on the frame 19 to bring the parts to their original position.

By means of my apparatus, it is possible to pass the tufting cords through the mattress at one time and to pass all of the cords through in the same time that it would take to pass one cord through the mattress by hand. It will be obvious that many changes may be made in the details of construction 45 of my mechanism without departing from the spirit of the invention and I do not wish to be limited to the exact construction illustrated.

Having described my invention, what I 50 claim is:

1. A mattress tufting machine comprising a main frame having vertically disposed spaced bars, a mattress clamping frame having spaced bars and hingedly mounted upon the main frame in front of the first named bars, a needle supporting frame mounted within the main frame for shifting movement toward or from said bars and carrying a plurality of forwardly extending needles, 55 and rearwardly shiftable needle supporting means mounted on the needle supporting frame.

2. A mattress tufting machine comprising a main frame having vertically disposed spaced bars, a mattress clamping frame hav-

ing spaced bars and hingedly mounted upon the main frame in front of the first named bars, a needle supporting frame mounted within the main frame for shifting movement toward or from said bars and carrying a plurality of forwardly extending needles, and a needle guiding frame shiftably mounted within the needle supporting frame and having a plurality of rods formed with notches through which the needles pass. 70 75

3. An apparatus of the character described comprising a main frame having vertically disposed rods at its forward end, a mattress clamping frame hingedly connected to the main frame in front of said rods and having vertically disposed rods, a needle carrying frame having wheels engaging the main frame for longitudinal movement relative to the main frame, the needle carrying frame at its forward end being provided with a plurality of spaced bars carrying forwardly extending needles, a needle supporting frame having wheels engaging the needle carrying frame for longitudinal movement relative thereto and having bars 80 85 extending forward between the bars of the needle carrying frame, and a plurality of rods mounted upon said outwardly extending bars and having notches with which the needles engage. 90 95

4. A mattress tufting machine comprising a main frame having longitudinal members, vertical members, transverse braces, a plurality of spaced vertical rods at its forward end, and a transverse platform in front of said rods, a mattress clamping frame hinged to said platform and having a plurality of spaced rods, means for holding the mattress clamping frame in clamping position, a needle carrying frame disposed within the main frame and having wheels engaging the longitudinal members of the main frame, the forward end of said needle supporting frame having spaced vertical bars and forwardly extending needles attached to said 100 bars, the needle carrying frame having upper and lower longitudinally extending members, and a needle supporting frame disposed within the needle carrying frame and having upper and lower longitudinally extending 105 members and vertical members, the upper and lower members extending forward beyond the vertical members and through the spaces between the vertical bars of the needle carrying frame, upper and lower pairs of 110 supporting wheels on the needle supporting frame engaging the longitudinal members of the needle carrying frame, transverse bars attached to the forwardly extending bars of the needle supporting frame, and vertical rods attached to said transverse bars and having notches in which the needles 115 120 125 slidingly engage.

5. A machine of the character described comprising a longitudinally movable car- 130

riage having a plurality of needles projecting from it, a mattress clamp disposed in front of said carriage, and needle supporting guides operatively mounted upon the carriage for rearward movement and having notches in which said needles slidingly engage.

In testimony whereof I hereunto affix my signature in the presence of two witnesses.
